(57) **CLAIM**

The ornamental design for an intercooler, as shown and described.

DESCRIPTION

FIG. 1 is a front perspective exploded view of the intercooler.

FIG. 2 is a front view of the intercooler.

FIG. 3 is a rear view of the intercooler.

FIG. 4 is a top view of the intercooler.

FIG. 5 is a bottom view of the intercooler.

FIG. 6 is a left side view of the intercooler.

FIG. 7 is a right side view of the intercooler.

FIG. 8 is an isometric view of the intercooler.

FIG. 9 is a front exploded view of the intercooler; and,

FIG. 10 is an isometric exploded view of the intercooler.

1 Claim, 10 Drawing Sheets
